Patented Sept. 9, 1975

236,742

TOY SHOP FRONT AND SIDE

Christine Goodwin, 8 Wilton Place,
London SW. 1, England

Filed Nov. 14, 1973, Ser. No. 415,734

Claims priority, application Great Britain July 30, 1973

Term of patent 14 years

Int. Cl. D21—01

U.S. Cl. D34—15 LL

FIG. 1

FIG. 3

FIG. 1 is a front perspective view of a toy shop front and side showing my new design;

FIG. 2 is a side perspective view thereof; and

FIG. 3 is a top plan thereof.

I claim:

The ornamental design for a toy shop front and side, substantially as shown and described.
